UNITED STATES PATENT OFFICE

JOHN C. CHAPPLER, OF ST. LOUIS, MISSOURI

BURNER

Application filed June 21, 1928. Serial No. 287,190.

This invention relates to improvements in burners; especially burners of fuel for use in connection with steam boilers and other power plants.

5 An object of the invention is to provide a burner which is constructed so that it can consume either solid fuel in pulverized form or liquid fuel or both together; and which is constructed to be especially adapted for use 10 upon locomotive boilers, stationary boiler furnaces and other installations.

Another object of the invention is to supply the pulverized fuel to the furnace in such a manner that the combustion and the attendant flame are spread out over the entire 15 interior. Hence any blast or erosive effect is dissipated and the heat of combustion is more evenly distributed through the furnace; without concentration of action in one 20 or more parts of the furnace walls or of the appliances associated therewith. The chief defect of the burners of pulverized fuel now in use is that they project the fuel mixed with air into the furnace in certain directions, with considerable blast effect. Consequently certain parts of the interior of the furnace remain relatively cold while others become extremely hot. This mode of action 25 results in a low fuel capacity and poor steam generating and heating. It also results in excessive wear at certain points of the system and necessitates frequent shut-downs for cleaning, repairs, renewals, etc.

A further object of the invention is to 30 equalize and modify the combustion of the pulverized fuel so as to eliminate undesirable effects and obtain the full efficiency of the furnace, together with thorough combustion of the fuel which the burner receives.

40 A still further object of the invention is to provide a burner in which the pulverized solid fuel, together with the air carrying it; and the liquid fuel when the latter is utilized, are fed into the furnace at one and the same 45 place. This feature facilitates the use of either pulverized solid fuel or liquid fuel, or both kinds of fuel in combination; and is of great advantage in localities where one kind of fuel is available while the other is 50 not. In either case efficient operation of the

burner can be obtained without any change in the construction of the boiler, or locomotive or the like in connection with which the furnace supplied by the burner is employed.

And yet another object of the invention is 55 to provide a burner in which the pulverized solid fuel and the air carrying it are supplied to the furnace through a number of passages, and which is so formed that it contains passages through which additional air is admitted to the furnace to complete the combustion. The passages through which the additional air passes on its way to the furnace are preferably located between or adjacent the passages through which the pulverized 60 solid fuel is caused to flow into the furnace; thus giving a better mixture of the air carrying the pulverized solid fuel and the air added to same. By this means the combustion can be made to take place quicker and with 65 a relatively short flame; which is particularly desirable in furnaces such as the furnaces of locomotives and stationary boilers having furnaces of relatively small size with no room for a long flame or travel of the fuel 70 a relatively great distance from the delivery end of the burner before the fuel is consumed.

Yet another object of the invention is to provide a burner for fuel adapted to receive additional air to assist the process of combustion and having means by which the additional air may be preheated as it enters the furnace.

A furnace according to this invention is 80 capable of a performance far superior to that of burners in which the fuel and air are projected into the furnace from different points and in different directions. In the practice of my invention, the admission of the fuel 85 and additional air to the furnace at one place not only increases the capacity of the furnace but also greatly simplifies the construction thereof.

The nature of the invention is fully disclosed in the following description taken 90 with the drawings on which the preferred form of my invention is illustrated. The disclosure, however, is explanatory only and changes may be made without departing 95 100.

from the spirit of the invention or exceeding the scope of the appended claims.

On the drawings,

5 Figure 1 is a vertical longitudinal sectional view of a locomotive furnace, for instance, with my burner attached;

Figure 2 is a horizontal section on the line 2—2 of Figure 1;

10 Figure 3 is a vertical section on the line 3—3 of Figure 4 taken through a portion of the furnace and showing the interior of the burner;

15 Figure 4 is a vertical longitudinal section on the line 4—4 of Figure 5, indicating the inside construction of the burner, and

Figure 5 is a top plan of the burner with the delivery end partly in section, on line 5—5 of Figure 4.

20 The same numerals identify the same parts throughout.

25 In this particular description of the construction shown in the drawings, I show at 1 a flash pan which in the practice of my invention replaces the ash-pan grates and riggings of the furnace of a locomotive boiler, for example. Of course while the device herein may be described in connection with the boiler of a locomotive it may be utilized for boilers of engines of a different design, such as stationary engines and power plants for other uses. The pan 1 may be lined with firebrick or any good refractory material 2; and the burner shown as a whole at 3 is mounted to deliver into the pan at the rear thereof. The numeral 4 may indicate diagrammatically the furnace, that is to say the end which is nearest to the rear of the locomotive on which the pan is placed. The top of the furnace is shown diagrammatically at 5 and 6 may be the fire tubes through which the hot gases of combustion pass to heat water in the boiler before they escape through the stack.

45 The burner 3 comprises a neck 7 having a flange 8 to enable it to be connected to a source of supply; and the end which enters the furnace is expanded over the top as indicated at 9. The burner has a number of passages 10 in the expanded top 9, through which pulverized solid fuel and the air carrying it are fed into the furnace, and below the top 9 are a pair of centrally-located passages 11 through which the same kind of fuel is introduced. Beneath the passages 11, which are 55 arranged side by side and at the middle of the bottom of the burner 3, may be an additional passage 12 through which fuel oil can be sprayed into the furnace by means of a suitable nozzle. The discharge end of the burner 60 is thus widest on top and narrowest at the bottom as indicated particularly on Figure 3, and the cross-section of the pan 1 will conform to the burner in shape. Therefore the sides of the pan will slope downward at a 65 given angle, as indicated at 13, and then more

sharply as indicated at 14 towards the bottom 15. The expanded end 9 of the burner may be disposed in the space between sides 13 while the sides 14 will flank the two passages 11 and the oil passage 12.

70 The expanded top 9 of the burner will also contain a pair of passages 16 through which additional air will be caused to flow into the flash pan 1. These passages 16 will lie between the fuel passages 10 along the extreme lateral edges of the expanded top 9 and the two passages 10 adjacent the middle of the burner. Between the two passages 10 adjacent the middle will be an air passage 17 of greater height than the passages 10, so that this air passage lies between the two fuel passages 11 also beneath this expanded top 9. This passage 17 will have extensions 18 between the two fuel passages 11 and the two passages 10 immediately above the passages 11, as indicated in Figure 3.

75 The fuel oil is fed through the passage 12 by means of a nozzle 19 therein connected to an oil supply pipe 20, and adjacent the nozzle 19 will be an injector nozzle 21 connected to a pipe 22 to receive steam or air and thus atomize the oil which issues from the nozzle 19.

80 In operation, if pulverized solid fuel is employed this kind of fuel in a state of division is caused to flow in a current of air through the neck 7 of the burner 3 to the point where the expanded top 9 begins and there the fuel spreads out and is fed into the furnace through the various passages 10, taking the direction indicated by the dot and dash lines with arrows on Figure 2. The fuel on entering the furnace is thus spread out fan wise and the flame of the fuel when combustion is in progress completely fills the furnace from one side to the other and even at the rear corners of the same. By thus increasing the width of the discharge end of the burner which enters the pan 1 and multiplying the fuel passages 10, the pressure and velocity of the pulverized fuel and air mixture which flows into the furnace is reduced and hence the combustion takes place in the furnace without any blast action. The result is a relatively short flame confined more or less to the rear of the furnace adjacent the burner where the incoming fuel enters. All the pulverized fuel and air, however, enter at one place and the short flame enables the combustion to be completed in a more effective manner as compared with burners which operate with a long flame reaching farther towards the end of the furnace in proximity with the fire tubes 6.

85 To heat additional air which flows into the furnace through the passages 16 and 17, with their extensions 18, I may provide the flash pan with a heating jacket 23, which is preferably located at the end where the burner 3 is mounted. This jacket 23 communicates 90

with a hood 24 enveloping the end of the burner which enters the furnace and the expanded top 9 may have an opening 25 covered by the hood so that the preheated air 5 can enter the passage 17 therethrough. A similar opening 25', communicating with the inside of the hood 24, may be formed in the bottom of the passage 17 just back of the nozzle 19; the two nozzles 19 and 21 as shown 10 in Figure 4 passing forward through the space 12, which, as indicated in Figure 4, is partitioned off so that it is not connected with the interior of the hood 24. I may also form lateral openings 26 in the sides of the burner 15 below the expanded top 9 so that preheated air can enter the extensions or pockets 18; these openings 26 also being within the hood 24. The under side of the expanded top 9 has additional openings 27, through the bottom 20 of the passages 16 for additional air heated in the jacket 23 to enter these passages and flow therefrom into the furnace above the pan 1. Of course the hood 24 will be of the proper size and shape to enclose the 25 openings 25, 26 and 27. If desired, of course, the hood and jacket can be omitted so that additional air will be supplied to the burner without preheating.

The pulverized solid fuel may be used 30 alone and so may the liquid fuel or oil, or both may be used together. This fact enables the burner to be operated to the best advantage because when one kind of fuel is not available the other can be selected, or where 35 both kinds can be obtained, the kind which is the most economical may be purchased.

The mechanical construction of the burner is indicated particularly in Figures 3, 4 and 5, and this burner may be made in any manner to give it the shape and the passages above described. It has a pair of longitudinal partitions 28, between which is the air passage 17 and these partitions diverge somewhat as indicated at 29, adjacent the discharge end 45 of the burner. The additional air passages 16 are each separated from the two fuel passages 10 on either side by the partition walls 30. Below the expanded top 9 the burner has vertical walls 31 which unite the passages 50 11 to the top, and the extensions 18 of the passage 17 lie between the top walls of the fuel passages 11 and the bottom wall of the top 9, indicated at 32. This bottom wall 32 terminates within the neck 7 at 33, and some of the 55 pulverized solid fuel flows past this edge and downward to pass through the passages 11 which thus are descending branch passages with respect to the passages 10 in the top. The top of the passages 11 and the bottom 60 walls of the passages 18 are separated by a web 34 between the vertical sides 31 of the inner end of the burner below the top 9, and the furnace may have an opening in its rear end, as indicated at 35; this opening serving as 65 a sight opening through which the process

of the combustion can be watched or for the introduction of ignition means when the furnace is to be lighted.

The burner can be mounted in the rear end of the pan 1 in any suitable manner which need not here be described. To begin the operation of the furnace, a little oil-soaked waste or shavings is ignited and thrown into the furnace on the bottom of the pan. The supply of fuel is then turned on and the process of combustion proceeds as desired. Of course either natural or mechanical means to provide a draft of air through the passages, 10, 16 and 17 can be employed.

All the fuel, whether solid or pulverized fuel or liquid fuel such as oil, is admitted into the furnace at one place, and with the shape of the burner expanded at its inner end and conforming to the inside shape of the pan 1 and the furnace above it, the combustion and the products thereof fill the furnace throughout the interior thereof and the largest possible heating effect and generation of steam is thus assured.

It will be seen from the above disclosure that my invention also involves a new method of burning pulverized fuel, in which a large volume of fuel under high pressure conveying air is delivered to the burner, the said fuel and air stream being sub-divided and the several fuel streams delivered into the combustion chamber of the furnace in a horizontal direction under greatly reduced pressure, and simultaneously additional combustion promoting air is drawn by induction into the combustion chamber at substantially the same rate of flow as the injected fuel streams, and preferably between the latter so as to aid in the lateral expansion of the fuel across the combustion chamber. By such a method, practically complete combustion of all of the pulverized fuel particles is obtained and with the desired short flame.

The jacket 23 may cover the whole or any part of the flash pan and it may have openings therein, shown at 36, wherever desired.

The invention can be employed in connection with any kind of boiler, movable or stationary, to furnish steam for heating or any other purpose.

Either compressed air or steam may be employed to atomize the oil at the nozzle 19.

The invention is particularly useful because it permits the consumption of certain kinds of solid fuel such as anthracite coal, which is relatively low in volatile matter. The utilization of low volatile anthracite slush or fines, in combination with high volatile fuel oil will provide a mixture that can be readily burned in pulverized form in suspension; whereas the low volatile anthracite alone could hardly be burned at all. Furthermore, in cases where the low volatile anthracite and high volatile bituminous coals or lignites are available, I can make a mixture

of these that can be satisfactorily burned in pulverized form in suspension.

Of course many changes might be made in the shape, size and arrangement of the various parts of the construction shown on the drawings herein without departing from the principle of the invention or exceeding the scope of the appended claims.

I claim:

- 10 1. A fuel burner for furnaces comprising a burner head having a single unitary structure adapted to be horizontally positioned through one end of the furnace, and having an upper horizontally elongated portion provided with pairs of fuel passages diverging in opposite directions from the center line of the burner head and also having a lower portion provided with longitudinally extending fuel passages below the inner adjacent fuel passages of the upper portion, said burner head having integrally formed means at the entrance ends of the fuel passages subdividing the entering body of fuel and distributing the same to the respective passages, and said burner head being further provided with air inlet passages separating the latter upper and lower fuel passages from each other and through which air is drawn by induced draft between the upper and lower streams of entering fuel.
- 15 2. A fuel burner for furnaces comprising a burner head having a single unitary structure adapted to be horizontally positioned through one end of the furnace, and having an upper horizontally elongated portion provided with pairs of fuel passages diverging in opposite directions from the center line of the burner head and also having a lower portion provided with longitudinally extending fuel passages below the inner adjacent fuel passages of the upper portion, said burner head structure being further provided with intercommunicating air inlet passages separating the last named individual upper and lower fuel passages horizontally and vertically from each other and through which segregating streams of air are drawn into the furnace with the entering fuel streams.
- 20 3. A fuel burner for furnaces comprising a burner head having laterally spaced pairs of fuel passages, the delivery ends of the pairs of passages diverging from the center line of the burner head and being disposed in a common horizontal plane, the outer passage of each pair being of less capacity than the inner passage, and said burner head having an additional pair of fuel passages located below the adjacent inner first named passages and through which fuel streams are discharged in angular relation to the path of projection of the fuel streams from said first named passages, and all of said passages at their other ends communicating with a common fuel inlet, and said burner head having integrally formed means at the latter end

of the fuel passages to subdivide the entering body of fuel and proportionately distribute the same to the respective passages.

In testimony that I claim the foregoing as my invention, I have signed my name hereto.

JOHN C. CHAPPLE.
